UNITED STATES PATENT OFFICE.

JERE G. KINGSBURY, OF WEST ORANGE, NEW JERSEY.

SPARKING PLUG.

No. 834,580.

Specification of Letters Patent.

Patented Oct. 30, 1906.

Application filed May 3, 1905. Serial No. 268,568.

To all whom it may concern:

Be it known that I, JERE G. KINGSBURY, a citizen of the United States, and a resident of West Orange, in the county of Essex and State of New Jersey, have invented certain new and useful Improvements in Sparking Plugs, of which the following is a specification.

My invention relates to an improvement in sparking plugs, the objects being to provide a device of this character which shall be simple in construction and yet durable, as well as one which will be less expensive to manufacture and which will effectually protect the electrodes or sparking points against injury; and to these ends my invention consists in providing a sparking plug the casing of which is removably secured to the combustion chamber or cylinder of an engine, which casing is adapted to contain and support the various elements of my invention without the use of auxiliary sections.

My invention further consists in certain novel details of construction and combinations of parts, such as will be more fully described hereinafter and particularly pointed out in the claim.

In the accompanying drawings, Figure 1 is a longitudinal cross-section through my improved sparking plug. Fig. 2 is an end view thereof, and Fig. 3 is a detail perspective view of the cup-shaped member or electrode.

A indicates the casing, which consists of a hollow metallic member externally threaded at its inner end and at its opposite end provided with a polygonal head to receive a wrench in placing and removing the plug. The bore of this casing is reduced at a point intermediate of its ends and is also provided with an internally-threaded portion 1, the outer end of the casing being provided with an inwardly-projecting flange 5 for a purpose hereinafter set forth.

The members of the sparking plug are introduced into the casing from the inner end. An insulating bushing or sleeve 3, having an external shoulder 4 formed thereon, is inserted through the inner end of the casing, the reduced portion 2 of the bore fitting snugly around the shoulder 4 of the sleeve and the inwardly-projecting flange 5 snugly embracing the periphery of the sleeve, an asbestos-like packing 6 being received within the bore of the casing between the flange 5 and the shoulder 4 of the sleeve, the packing being capable of withstanding a high degree of heat

and forming a gas-tight joint at that point. Seated against the opposite or inner face of the shoulder 4 is a ring or washer 7, which may be of wire and is retained in place by means of a cup-shaped member 8, provided with exteriorly-formed threads engaging the internal threads in the bore of the casing.

The sleeve 3 is provided with the usual channel extending longitudinally therethrough, the inner end of which channel being enlarged, as at 9, to form a shoulder against which rests the head 10 of a bolt 11, the body portion of the bolt passing through the channel and extending some distance beyond the outer end of the sleeve. This bolt is threaded at its outer end to receive a lock-nut 12, and between the nut and the outer end of the sleeve are located a binding-nut 13, slightly recessed on its inner face, and a packing-washer 14, the latter received between the recessed face of the binding-nut 13 and the outer end of the sleeve and operating to form an elastic connection between the sleeve and nuts. An electric connection is secured between the lock-nut 12 and the binding-nut 13, which latter, in conjunction with the bolt 11, form a binding-post.

The headed end of the bolt is provided with a sparking point 15 in the form of a wire, which passes through the enlarged portion of the channel in the sleeve to a point beyond the inner end thereof and adjacent the cup-shaped member 8, the latter being apertured, as at 16, in alignment with the channel in the sleeve. The inner end of the wire extends within the circumference of the aperture and is bent to approach the periphery thereof, the cup-shaped member constituting the opposing sparking points or electrodes. The wire 15 is preferably of a kind known to the trade as "meteor" wire and is received in a hole drilled or otherwise formed in the head of the bolt 11. The sparking points or electrodes do not extend beyond the inner end of the casing A, and hence are protected thereby against injury. The aperture 16 of the cup-shaped electrode is of less diameter than the chamber or space inclosed by such member, to the end that the rush of gases on the outstroke of the piston will pass rapidly through the constricted opening thus formed and keep the sparking points and the chamber inclosed by the cup-shaped member clean by ridding them of any particles of soot which may accumulate thereon.

From the foregoing it will be observed that I have devised a simple, neat, and durable device consisting of but few parts and one which can be readily removed and replaced, 5 the various elements composing the plug being easily accessible for cleaning, if necessary, and for the substitution of new parts for old or worn-out ones, as well as for adjustment. It will further be observed that in assembling the parts in the manner set forth there is absolutely no danger of their being blown out by the pressure within the cylinder. It is evident, therefore, that slight changes might be resorted to in the form and arrangement of the several parts described without departing from the spirit and scope of my invention, and hence I do not wish to limit myself to the precise construction herein set forth.

20 Having thus fully disclosed my invention, what I claim as new, and desire to secure by Letters Patent, is—

25 A sparking plug comprising a tubular open-ended casing which is externally threaded and provided at its outer end with an internal annular flange and internally threaded at a point intermediate of its ends, a tubular non-conducting bushing or sleeve projecting outwardly through the outer end of the casing 30 with its inner end terminating short of the inner end of the casing, said bushing or sleeve be-

ing snugly embraced by the flange and having an annular external flange within the casing, packing between the two flanges, a cup-shaped terminal having external threads and fitted to the internally-threaded part of the casing in coöperative engagement with the flange of the non-conducting bushing or sleeve to removably hold the latter in place, the other end of said terminal having a central opening of less diameter than the terminal and lying within the casing, there being an annular space between the terminal and the non-conducting bushing or sleeve, the inner end of the bore of the bushing or sleeve being enlarged, a conductor extending through the bore of the bushing or sleeve and provided with a head in the enlarged portion thereof, a terminal extending from the head outwardly through the inner end of the bushing or sleeve and deflected 50 into close proximity to the opening in the cup-shaped terminal, said conductor having a threaded portion projecting beyond the outer end of the bushing or sleeve, and a nut fitted thereon.

55 Signed at West Orange, in the county of Essex and State of New Jersey, this 25th day of April, A. D. 1905,

JERE G. KINGSBURY.
